UNITED STATES PATENT OFFICE.

JAMES D. FARMER, OF ST. LOUIS, MISSOURI.

COMMODE.

SPECIFICATION forming part of Letters Patent No. 629,434, dated July 25, 1899.

Application filed September 17, 1898. Serial No. 691,252. (No model.)

To all whom it may concern:

Be it known that I, JAMES D. FARMER, a citizen of the United States, residing at the city of St. Louis, in the State of Missouri, have 5 invented a certain new and useful Improvement in Commodes, of which the following is a full, clear, and exact description, reference being had to the accompanying drawings, forming part of this specification.

10 My invention relates to a portable commode that can be readily cleaned and which is kept perfectly sealed when in use.

My invention consists in features of novelty hereinafter fully described, and pointed out 15 in the claims.

Figure I is a perspective view of my commode. Fig. II is a vertical section. Fig. III is a view of the under side of the hinged seat of the commode, the seat being shown in section. Fig. IV is an enlarged detail section.

20 1 represents a stand, the legs 2 of which are hinged to the top 3, as shown at 4, so as to be folded, as represented by dotted lines, Fig. I, the legs being held in their open position by braces 5.

25 6 represents the seat, hinged at 7 to the top 3. To the under side of this seat is removably secured a sack 8 by means of a ring 9, through which the mouth of the sack is passed 30 and turned over, as shown in Fig. IV. The ring is hinged to the under side of the seat at 10 and is held in its closed position by turn-buttons 11.

35 12 represents a packing tube or ring secured by flanges 13 to the under side of the seat and against which the sack is held by the ring 9, so as to make a perfectly tight

joint. The sack is thus held to the seat in a manner that permits of its ready and easy removal when after use the sack is to be thrown 40 away and replaced by another.

The cover 14 of the article is hinged to the seat at 15 and is provided with a packing-strip 16 and a catch 17, whereby it may be held air-tight upon the seat. 45

By making the sack 8 of flexible material, such as oiled cloth or rubber, and by hinging the legs the article as a whole can be folded into a compact bundle when not in use, and when the sack is removed the mouth 50 of it can be closed to seal the contents.

I claim as my invention—

1. A commode comprising a seat and support therefor, a bag, and a hinged ring by which said bag is removably secured to the 55 under side of said seat, substantially as set forth.

2. A commode comprising a seat and support therefor, a packing-ring secured to the under side of said seat, a bag and a ring for 60 removably holding said bag against said packing-ring, substantially as set forth.

3. A portable commode comprising a seat and a support therefor, a packing-ring secured to the under side of said seat, a bag, a 65 ring for removably holding the bag against said packing-ring, and a lid hinged to the seat and having a packing-strip 16, substantially as set forth.

JAMES D. FARMER.

In presence of—

E. S. KNIGHT,
N. V. ALEXANDER.
